CONVERSION OF HYDROCARBONS

Claude W. Watson, Tuckahoe, N. Y., assignor, by
mesne assignments, to The Texas Company,
New York, N. Y., a corporation of Delaware

Application May 24, 1941, Serial No. 394,979

4 Claims. (Cl. 196—9)

This invention relates to the cracking and coking of hydrocarbon oils to produce lower boiling hydrocarbons and to the gas reversion or polymerization of normally gaseous hydrocarbons into higher boiling hydrocarbons, so as to obtain maximum yields of products within the gasoline or motor fuel boiling range. The invention is especially adapted for the processing of petroleum residual stocks, such as topped or reduced crudes, to obtain maximum yields of gasoline therefrom. The invention is concerned particularly with a process wherein condensate obtained in the process is recycled to a cracking zone and the cracked products combined with a petroleum residual stock for cracking and wherein normally gaseous hydrocarbons are recycled for conversion and residual products subjected to coking.

In this type of process when all of the cracked products produced in the cracking or conversion of the recycle gases and condensate and the residual stock are flashed from the reaction zone into the coking zone the resulting coking operation is normally accompanied with priming in the coking drum. If, on the other hand these cracked products are separated into vapors and residue and only the separated residue delivered to the coking zone the autogenous heat of the residue is insufficient to effect coking. The temperature limitations imposed on the reaction zone to prevent coking therein are such that it is impossible to obtain sufficient heat in the residue to accomplish autogenous coking. In accordance with the invention separation of vapors from residual constituents is carried on in the reaction zone and a portion of the vapors sufficient to effect coking is withdrawn with the residual constituents and flashed in the coking zone, while the remaining vapors are separately withdrawn from the reaction chamber. In this way it is possible to operate even with high recycle rates without coke drum priming.

In accordance with the invention the reaction products produced by subjecting the cycle condensate and the recycle gases to conversion are combined with petroleum residual constituents for reaction in a reaction chamber wherein separation of vapors from liquid residue occurs, the liquid residue together with a sufficient portion of the vapors to effect coking is passed into the coking drum wherein conversion to coke takes place, the remaining separated vapors from the reaction chamber and evolved vapors from the coking chamber are dephlegmated with a petroleum residual stock to form a resultant mixture of heavy reflux condensate and residual stock. The vapors are further fractionated to separate reflux condensate from lighter hydrocarbons, the reflux condensate is cycled to a heating zone wherein it is subjected to cracking temperature and the resultant heated products are combined

with the mixture of heavy reflux condensate and residual constituents for reaction in the reaction chamber, the lighter hydrocarbons separated from the reflux condensate in the fractionator 5 are subjected to further fractionation to separate normally liquid hydrocarbons such as gasoline from normally gaseous hydrocarbons and normally gaseous hydrocarbons are cycled to the heating zone for conversion together with the cycle condensate or are cycled to a separate polymerizing zone and the resultant products of polymerization directed to the reaction chamber.

In practicing the invention the vapors from the coking operation may be subjected to a primary cooling or dephlegmation, the uncondensed vapors combined with the vapors which are separately withdrawn from the reaction chamber and the combined vapors dephlegmated with the petroleum residual charging stock to produce a 10 mixture of reflux condensate and unvaporized residue for combining in the reaction zone with heated products produced in the heating of the lighter cycle condensate and recycled gases. By subjecting the vapors from the coking operation to a primary dephlegmation a heavy tarry condensate is produced which is adapted for fuel oil so that the operation may be conducted so as to simultaneously produce coke and fuel oil in addition to the gasoline or motor fuel product.

15 For the purpose of more fully disclosing the invention reference is had to the accompanying drawing which is a flow diagram illustrating apparatus adapted for the practice of the invention.

20 The apparatus shown in the drawing includes a reaction chamber A, a coking drum B, a primary fractionating tower C and a secondary fractionating tower D. Separation of vapors from liquid residue takes place in the chamber A from which liquid residue together with a portion of the vapors is passed through line 10 and pressure reducing valve 11 to the coking chamber B. Vapors from the coking chamber pass through 25 line 12 to a primary dephlegmating section 13 of the tower C. Vapors are separately withdrawn from the reaction chamber A through a vapor line 14 which conducts the vapors to a fractionating section 15 of the tower C above a trapout tray 16.

crude in a heated condition directly from the topping or reducing stills and a line 21 is indicated for so introducing the hot residue.

The tarry condensate obtained in the dephlegmating section 13 from the primary dephlegmation of the vapors from the coking drum B may be withdrawn as a liquid fuel product through a line 22. The mixture of heavy reflux condensate and unvaporized topped or reduced crude collecting in the tray 16 is withdrawn through a line 23 by a pump 24. When it is not desired to withdraw the bottoms from dephlegmator 13 as a separate product the tray 16 may be permitted to overflow and the mixture of heavy condensate and unvaporized residue withdrawn through line 22 and passed through a branch line 25 into the line 23. The pump 24 directs the oil, as withdrawn either from section 13 or from trap-out tray 16, through a line 26 to a heating coil 27 disposed in a furnace 28 and the heated products pass through a transfer line 29 to the reaction chamber A.

In some cases the heating of the heavy oil in the coil 27 may be omitted and the oil by-passed through a line 30 directly to the transfer line 29 thence to the reaction chamber A.

Vapors uncondensed in the tower C pass through a line 31 to the fractionator D wherein the vapors are fractionated to separate higher boiling reflux condensate from lighter vapors and gases. The reflux condensate is withdrawn by a pump 32 and directed through a line 33 to a heating coil 34 disposed in a furnace 35 and the heated products are passed through a transfer line 36 to the reaction chamber A or to the transfer line 29 so as to combine the heated products with the heavy oil stock being delivered from the heating coil 27 or from the by-pass line 30.

Uncondensed vapors from the tower D pass to a condenser 37 and the distillate is collected in a receiving drum or gas separator 38. The drum 38 is maintained under superatmospheric pressure and normally gaseous hydrocarbons, predominantly methane and C₂ hydrocarbons, as well as hydrogen, are removed through a gas line 39 while the gasoline or naphtha distillate containing normally gaseous hydrocarbons, predominantly C₃ and C₄ hydrocarbons, is collected as a liquid in the drum. The liquid distillate is withdrawn by a pump 40 and conducted through a line 41 to a rectifying tower 42 wherein the distillate is subjected to rectification or stabilization to remove normally gaseous hydrocarbons and the rectified product is withdrawn through a line 43. The uncondensed gases pass to a condenser 44 thence to a receiving drum 45 having a gas outlet 46. The liquid distillate in the drum 45 comprising predominantly C₃ and C₄ hydrocarbons is withdrawn by a pump 47 and directed through a line 48 to a heating coil 49 disposed in a furnace 50. The heated products pass through a transfer line 51 to the reaction chamber or transfer line 29 so that the heated products may be combined with the other products undergoing reaction in reaction chamber A. The normally gaseous hydrocarbons being passed through the coil 49 may be subjected to temperature pressure conditions therein adequate to effect polymerization into liquid hydrocarbons. In an alternative operation the normally gaseous hydrocarbons may be merely preheated in coil 49 and then directed through a branch line 52 for combining with the cycle condensate being passed through the heating coil 34 wherein the mixture of normally liquid and normally gaseous hydrocarbons is subjected

to reversion reactions for the production of liquid products in the gasoline boiling range.

In practicing the invention with the apparatus illustrated, topped or reduced crude is preheated by heat exchange with hot products of the cracking system or is drawn in a heated condition directly from topping or reducing stills or is heated in the coil 18 and the heated residuum introduced into the tower C. Constituents of the nature of kerosene and gas oil are distilled off the residue in the tower C and passed to the tower D together with cracked constituents from which tower the reflux condensate is cycled to the cracking or conversion coil 34. The gasoline distillate is collected in the receiver 38 and the gasoline is stabilized in the tower 42 under superatmospheric pressure. The overhead from the tower which collects in receiver 45 consists essentially of the heavier of the normally gaseous hydrocarbons, more particularly C₃ and C₄ hydrocarbons. A portion of the distillate collecting in the receiver 45 is normally employed for refluxing the tower 42 and the remainder is directed to the coil 49 wherein it is subjected to polymerizing temperatures such as temperatures of the order of 900° F. and 1000° F. under pressures of the order of 500 to 1000 lbs. and the resultant products of conversion are directed to the reaction chamber A for further reaction with the other hydrocarbons therein. If it is not desired to subject the C₃C₄ fractions to separate polymerization the coil 49 may be used as a preheating coil and the preheated normally gaseous hydrocarbons combined with the reflux condensate passing from the tower D to the conversion coil 34. In some cases it is advantageous to subject the normally gaseous hydrocarbons in the coil 49 to high temperatures of the order of 1000 to 1200° F. to effect an increase in the olefin content thereof and combine the resultant products of conversion with the cycle condensate in the coil 34. In the coil 34 the mixture of normally liquid hydrocarbons and normally gaseous hydrocarbons is subjected to temperatures of the order of 900° F. or 1000° F. under pressures such as 400 to 800 lbs. to effect cracking and reversion reactions and to concomitantly effect conversion of higher boiling normally liquid hydrocarbons into lower boiling products and conversion of normally gaseous hydrocarbons into higher boiling hydrocarbons within the gasoline boiling range. The products of conversion are combined with the black oil introduced directly from the tower C through line 30 or after heating in the coil 27 for further reaction in the reaction chamber A.

It is advantageous to subject the topped or reduced crude to viscosity breaking in the coil 18 before introducing to the tower C. In such an operation the heating in the coil 27 of the mixture of unvaporized residuum and reflux condensate which is drawn from the tower C may generally be omitted and the mixture may be combined directly with the hot products from the reversion coil 34 or with the hot products from both heating coils 34 and 49. When employing the coil 27 the black oil stock is subjected to cracking or viscosity breaking therein under temperatures of the order of 800° F. or 900° F. and under pressures such as 200 to 600 lbs.

The reaction chamber A should be maintained under pressures at least as high as about 200 lbs. and preferably under pressures of the order of 300 to 600 lbs. It is desirable to maintain somewhat high pressures in the tower A in order to promote continued reactions of the nature of

reversion and polymerization to promote conversion of the normally gaseous hydrocarbons as well as to effect continued conversion of higher boiling liquid constituents into lower boiling products of the gasoline boiling range. The temperature in the reaction chamber A should be upwards of 850° F. so as to maintain a sufficiently high rate of cracking therein as to promote conversion into antiknock gasoline constituents. It is preferred to maintain in the reaction chamber A as high a temperature as is possible without coking and this temperature will ordinarily be in the neighborhood of 900° F.-930° F. Liquid is prevented from accumulating in the chamber A by the rapid withdrawal of the liquid residue through the line 18. While a single downflow reaction chamber has been illustrated it is to be understood that the reaction zone in which the commingled products from the heating coils are subjected to reaction may assume various forms. For example, it is advantageous to provide an initial downflow reaction chamber with all of the products, both vapors and liquid, passing together without separation into a subsequent upflow reaction chamber from which vapors are withdrawn at the top and a mixture of vapors and liquid residue withdrawn from the bottom for passage to the coking drum. Another advantageous arrangement is to provide a counterflow reaction chamber with the black oil stream being introduced to an upper portion and the stream from heater 34 being admitted to a lower portion of the chamber.

The temperature required for coking depends on the pressure and the character of the stock introduced into the coking drum. In general a temperature in excess of 825° F. is required in order to effect coking for the production of a marketable coke and the temperatures used will ordinarily be about 840° F. to 885° F. A temperature, for example, of 850° F. under pressures of 150 to 175 lbs. in the coking drum is quite satisfactory. The passage of material from the reaction chamber A through the line 18 to the coking drum B is controlled so as to continuously pass all of the liquid together with a sufficient portion of the vapors to maintain the desired coking temperature in the coking drum without causing priming through the vapor line of the coking drum. A relatively small proportion of the vapors is required for this purpose, a proportion approximately of the order of 10% of the total vapors leaving the reaction chamber. By operating in this manner it is possible to obtain charging rates and recycling rates, that is, rates of recycling for the cycle condensate and recycle gases and for the black oil, of an extremely high magnitude, which it has been impossible to reach in prior methods of operation. For example, on equipment in which the limit in the gas oil recycling rate was within the range of 230 to 280 bbls. per hour in order to avoid priming in the coking drum, the practice of the invention makes possible the raising of such recycling rate up to 400 to 500 lbs. per hour without priming. When running to coke only, that is, when not making a distillate fuel oil product in dephlegmator 13, the practice of the invention enables the raising of the charging rate from about 80 barrels per hour to about 125 barrels per hour and when running to both coke and distillate fuel, charging rates of the order of 180 to 200 bbls. per hour may be obtained.

The fractionating towers C and D are advantageously maintained under pressures approxi-

mating the coking drum pressure. A relatively small amount of cooling is applied to the dephlegmator 13, as by the introduction of a small amount of cycle condensate, in order to prevent coking in the dephlegmator. When running to coke only the temperature in the dephlegmator may be maintained without coking at a somewhat higher range than when drawing a fuel oil product from the dephlegmator. Thus, for example, in the coke only operation temperatures of around 810° F. to 820° F. may be maintained in the dephlegmator and when running to coke and fuel oil temperatures of about 790° F. to 800° F. may be maintained. When running to coke and distillate fuel oil the mixture of unvaporized residuum and reflux condensate may be withdrawn from the tray 16 at temperatures approximately 800° F. The top of the tower C may be maintained at temperatures approximating 710° F. to 730° F. under about 150 lbs. pressure and the bottom of tower D may be held at temperatures around 660° F. to 690° F.

In general the higher the pressure applied in the coking drum the greater will be the yield of coke and when running to coke and distillate fuel oil the higher the pressure the greater the ratio of coke to fuel oil. The pressure carried in the coking drum may accordingly be varied somewhat in accordance with the requirements for coke and fuel oil. It is desirable however to maintain sufficient pressure in the coking drum to insure the proper separation in the receiving drum 38. In other words, in order to obtain the desired retention of C₃ and C₄ hydrocarbons in the distillate withdrawn from the receiver 38 it is desirable that the pressure should be at least as high as 100 lbs. and preferably 150 lbs. or more. When the coking operation is carried on under low pressure such as 50 lbs. it may be desirable to subject the gases passing through the line 39 to additional fractionation or absorption in order to recover C₃ and C₄ hydrocarbons therefrom. In an alternative method of operation the towers C and D are maintained under pressures approximating the pressure in the reaction chamber A and under pressures of 200 lbs. or higher which insures a very good separation in the receiver 38, while the coking drum is operated under any desired low pressure such as around 50 lbs. and the vapors from the coking drum are separately condensed and the distillate refluxed on either or both of the towers C and D.

While I have described a particular embodiment of my invention for purposes of illustration, it should be understood that various modifications and adaptations thereof which will be obvious to one skilled in the art, may be made within the spirit of the invention as set forth in the appended claims.

I claim:

1. In the conversion of hydrocarbons for the production of gasoline, the process that comprises subjecting a mixture of cycle condensate and normally gaseous hydrocarbons to conversion temperature in a conversion zone to effect conversion into gasoline constituents, combining the resultant products of conversion with residual constituents of crude petroleum for reaction in a reaction zone maintained at cracking temperature under superatmospheric pressure and wherein separation of vapors from liquid residue takes place, preventing the accumulation of liquid in said reaction zone by rapidly withdrawing the liquid residue, including a portion of the

vapors with the liquid residue thus withdrawn from the reaction zone in quantity sufficient to effect the autogenous coking thereof and delivering the mixture to a coking zone maintained under reduced pressure wherein coking takes place without priming, separately withdrawing vapors from said reaction zone, subjecting evolved vapors from the coking zone and separated vapors from the reaction zone to fractionation to separate a condensate from heavier and lighter constituents, cycling said condensate to the aforesaid conversion zone, subjecting said lighter constituents to further fractionation to separate normally liquid hydrocarbons from normally gaseous hydrocarbons comprising C_3 and C_4 hydrocarbons and cycling such normally gaseous hydrocarbons to said conversion zone.

2. In the conversion of hydrocarbons for the production of gasoline, the process that comprises subjecting a mixture of cycle condensate and normally gaseous hydrocarbons to conversion temperature in a conversion zone to effect conversion into gasoline constituents, combining the resultant products of conversion with hydrocarbon oil as hereinafter specified for reaction in a reaction zone maintained at cracking temperature under superatmospheric pressure and wherein separation of vapors from liquid residue takes place, preventing the accumulation of liquid in said reaction zone by rapidly withdrawing the liquid residue, including a portion of the vapors with the liquid residue thus withdrawn from the reaction zone in quantity sufficient to effect the autogenous coking thereof and delivering the mixture to a coking zone maintained under reduced pressure wherein coking takes place without priming, separately withdrawing vapors from said reaction zone, dephlegmating evolved vapors from the coking zone and separated vapors from the reaction zone with a crude petroleum residual stock to produce a mixture of residual stock and heavy reflux condensate, utilizing said mixture as the hydrocarbon oil being combined with the products from said conversion zone for reaction in said reaction zone, subjecting the dephlegmated vapors to further fractionation to separate reflux condensate from lower boiling hydrocarbons, cycling said reflux condensate to said conversion zone, subjecting the separated lower boiling hydrocarbons to further fractionation to separate normally liquid hydrocarbons from normally gaseous hydrocarbons comprising C_3 and C_4 hydrocarbons and cycling such normally gaseous hydrocarbons to said conversion zone.

3. In the conversion of hydrocarbons for the production of gasoline, the process that comprises subjecting a mixture of cycle condensate and normally gaseous hydrocarbons to conversion temperature in a conversion zone to effect conversion into gasoline constituents, combining the resultant products of conversion with hydrocarbon oil as hereinafter specified for reaction in a reaction zone maintained at cracking temperature under superatmospheric pressure and wherein separation of vapors from liquid residue takes place, preventing the accumulation of liquid in said reaction zone by rapidly withdrawing the liquid residue, including a portion of the vapors with the liquid residue thus withdrawn

from the reaction zone in quantity sufficient to effect the autogenous coking thereof and delivering the mixture to a coking zone maintained under reduced pressure wherein coking takes place without priming, separately withdrawing vapors from said reaction zone, dephlegmating evolved vapors from the coking zone in a dephlegmating zone to form a heavy tarry condensate, passing the dephlegmated vapors to a second dephlegmating zone, directing separated vapors from said reaction zone to the second dephlegmating zone and dephlegmating the vapors therein with a petroleum residual stock, utilizing the resultant mixture of residual stock and heavy reflux condensate as the hydrocarbon oil being combined with the products from said conversion zone for reaction in said reaction zone, subjecting the latter dephlegmated vapors to further fractionation to separate reflux condensate from lower boiling hydrocarbons, cycling said reflux condensate to the aforesaid conversion zone, subjecting said lower boiling hydrocarbons to further fractionation to separate normally liquid hydrocarbons from normally gaseous hydrocarbons comprising C_3 and C_4 hydrocarbons and cycling such normally gaseous hydrocarbons to said conversion zone.

4. In the conversion of hydrocarbons for the production of gasoline, the process that comprises subjecting cycle condensate formed as hereinafter specified to conversion temperature under superatmospheric pressure in a conversion zone to effect conversion into gasoline constituents, combining the resultant products of conversion with hydrocarbon oil as hereinafter specified for reaction in a reaction zone maintained at cracking temperature under superatmospheric pressure and wherein separation of vapors from liquid residue takes place, preventing the accumulation of liquid in said reaction zone by rapidly withdrawing the liquid residue, including a portion of the vapors with the liquid residue thus withdrawn from the reaction zone in quantity sufficient to effect the autogenous coking thereof and delivering the mixture to a coking zone maintained under reduced pressure wherein coking takes place without priming, separately withdrawing vapors from said reaction zone, dephlegmating evolved vapors from the coking zone and separated vapors from the reaction zone with a petroleum residual stock to produce a mixture of residual stock and heavy reflux condensate, utilizing said mixture as the hydrocarbon oil being combined with products from the conversion zone for reaction in the reaction zone, subjecting the dephlegmated vapors to further fractionation to separate reflux condensate from lower boiling hydrocarbons, directing said reflux condensate to said conversion zone, subjecting said lower boiling hydrocarbons to further fractionation to separate normally liquid hydrocarbons from normally gaseous hydrocarbons comprising C_3 and C_4 hydrocarbons, subjecting said normally gaseous hydrocarbons to conversion temperature under superatmospheric pressure to effect conversion into higher boiling constituents within the gasoline boiling range and directing the resultant products of the latter conversion to said reaction zone.

70 CLAUDE W. WATSON.
